Specification of Letters Patent.

Patented Nov. 6, 1917.

Application filed June 16, 1915. Serial No. 34,411.

To all whom it may concern:

Be it known that I, HARRY W. BOLENS, a citizen of the United States, residing at Port Washington, in the county of Ozaukee 5 and State of Wisconsin, have invented a new and useful Tilting-Chair, of which the following is a specification.

This invention relates to improvements in tilting-chairs, having particular reference 10 to that part thereof commonly termed the "iron"—in reality, the adjustment for supporting, raising, and lowering the seat. A very popular style of "iron" now in general use, includes a sheet-metal stretcher or 15 bridge, made usually more or less of inverted U-shape, the same being suitably mounted upon the yoke, and embodying or carrying the stops for limiting the tilting movement of the seat, the tension-spring and 20 spider-arms. The spider-arms have, heretofore, been applied either to the tops of the stretcher or bridge or to the corners, whereby the attaching-ends of the arms occur at an elevation above the horizontal plane of 25 the stretcher or bridge. When thus mounted, the "iron" as a whole occupied very considerable space, to allow for which, the chair-base, by which I mean the claws or legs, had to be made squatly and unsightly 30 and out of symmetry with the remainder of the chair. One of the objects of my invention is, therefore, to overcome this defect by so locating and disposing the spider-arms that while yet retaining the same graceful 35 outline of design, they terminate or have their attaching-ends occur in substantially the same horizontal plane as the upper surface of the stretcher or bridge. This arrangement materially decreases the height 40 of the "iron," with the result, that the chair-base may be made in proper proportion and the chair-seat when lowered will not be abnormally high.

A further object of the invention is to 45 utilize a rigid supporting-post—that is, a post rigid with the chair-base—substituting the post for the usually-employed threaded post working in the chair-base; the stretcher or bridge and the yoke carrying the same 50 being mounted for vertical movement on the rigid post, whereby to secure proper elevation of the chair-seat, the whole, with the exception of the post, being capable of freely revolving on the chair-base. By substituting 55 the rigid guide-post for the threaded post, looseness of the latter in the chair-

base, as caused by wear, is avoided, and the life of the chair greatly increased.

Other, though minor, objects of my invention, will hereinafter appear, and the novel 60 features thereof will be particularly pointed out in the claims.

Referring to the drawings—

Figure 1 is a vertical, central, longitudinal sectional view, partly in side elevation, of a 65 "chair-iron" embodying my invention;

Fig. 2 is a top plan view of the same;

Fig. 3 is a front elevation of the "iron," parts being shown in vertical section; and,

Fig. 4 is a rear elevation of the "iron," 70 parts being shown in vertical section.

Similar numerals of reference indicate similar parts in all the figures of the drawings.

The chair-base 5, may be of any preferred 75 design, such forming no part of my invention, and secured to it and rising therefrom, is a rigid cylindrical guide-post 10. This post, it will be understood, may be fastened to the chair-base 5, as for instance, by a pin 80 6, the post extending down into a bore formed in the base, or, it may be secured to the base otherwise, or formed integral with the metal part of the base. A ball-race 7, may be formed annularly about the post 85 10, the race being formed in the upper side of a metal plate 8, that caps the base 5. Swiveled about the post, above the cap, and having a companion ball-race 16, formed in its underside, is a turn-table 15, the same being preferably formed circular, and between 90 these two—the cap 8 and the turn-table 15, within the races,—is a series of anti-friction balls 17.

The carrier-yoke 20, is of substantially 95 right angular shape, and embodies a vertically bored elongated hub 21, mounted to slide upon the rigid guide-post and upon which it is also capable of freely rotating; a rear vertical extension 22 rising to a point 100 slightly above the hub 21; and at the opposite side of the hub or front, a forward horizontal extension 23.

In the latter extension there is formed a 105 vertically disposed threaded opening 24, the threads of this opening engaging similar threads formed on an adjusting-screw 25, the lower end of which enters a plain opening 19, formed in the turn-table 15. The lower end of this screw is cylindrical, forming a head 26, swiveled in the opening 19, and at about its middle, may be formed with

2
an annular groove 26^a, a retaining-screw 27, passing through the side of the turn-table and engaging the groove 26^a, whereby, while the adjusting-screw 25 is free to rotate, yet it cannot be withdrawn without first withdrawing the screw 27. Immediately above the head 26, the adjusting-screw is provided with a milled-nut 28, the same being fixed upon the adjusting-screw and adapted to 10 rotate the same whereby to feed the yoke 20 up or down, as the case may be, upon the guide-post 10. In this manner I provide for a raising and lowering of the yoke, and the chair-seat carried thereby, whereby the latter may be given the desired elevation, the whole being capable of revolving with the turn-table 15 in a manner obvious.

The stretcher 30, is preferably of substantially U-shape, comprising in the present instance, as it does, the opposite depending side-ears 31, and the upper connecting cross-piece 32. The ears embrace the yoke, and through the latter and the ears passes a transverse pintle 33, whereby the stretcher becomes pivotally mounted upon the yoke. To provide for the passage of the upper end of the guide-post 10, the front edge of the cross-piece 32 of the stretcher may be recessed as at 34, and front and rear depending stop-lugs 35 and 36, respectively, may be punched from the cross-piece 32 and lie in front and in rear of the rear vertically projecting extension 22 of the yoke, the upper end of which extension occurs directly 35 under the aforesaid cross-piece.

The extension 22 of the yoke is provided with a transverse perforation 37, over the front of which is the usual washer 38, perforated to receive the tension-bolt 39, which 40 also passes through the perforation 37 of the extension 22. The rear end of this bolt 39 is provided with a hand-wheel or nut 40, and between the same and the flange 38^a, of the yoke, there is mounted on the bolt, the 45 usual adjusting-spring 41, these parts being of the usual construction, though the bolt is disposed rearwardly instead of forwardly, as is usual, whereby to avoid the sleeve 21 of the yoke. This arrangement, of course, 50 brings the hand-wheel 40 at the rear instead of at the front of the adjustment.

The spider-arms 42, are bowed and formed of sheet-metal, all in the usual manner, and terminate in the perforated attaching-ends 55 43. Heretofore, such arms have been located at the upper angles of the stretcher, the angles of the arms conforming more or less with the corners or angles of the stretcher. This arrangement, as heretofore stated, 60 caused the attaching-ends to occur at a point above the stretcher, and hence, the chair-seat was likewise elevated to the same extent above the adjustment. In the present instance, I reverse the spider-arms—that is 65 to arrange the angles outwardly,—and rivet

the vertical flanges 44 thereof to the depending side-ears 31 of the stretcher, well down upon the same, as indicated at 45. This arrangement secures a two-fold advantage, namely, it lowers the attaching-ends of the 70 spider-arms until they are in the same horizontal plane of the stretcher, and, since the pintle also passes through the vertical flange 44 of the arms, this arrangement reinforces the side-ears of the stretcher by practically 75 doubling the thickness, and this too, at the points where the greatest strain and wear occur in the stretcher.

In this manner, and by my invention, it will be seen that the adjustment resulting is 80 most compact and strong and capable of long and hard usage without the parts working loose; that greater rigidity is given the stretcher without adding material, weight, or cost; and finally, the chair-seat is supported at such a distance above the floor as 85 good design dictates without sacrificing the appearance of the chair-base.

Having described my invention, what I claim, is:

1. The combination, in a chair, of a base, a fixed guide-post rising vertically therefrom, a turn-table swiveled on the post and freely rotatable on the base, a vertically movable yoke substantially right angular in shape and consisting of an intermediary hub or sleeve slidably mounted on said post and at one side of the hub or sleeve having a front horizontal extension and at the opposite side a vertical extension, means carried by the turn-table and connected to the front horizontal extension of the yoke whereby to adjust the yoke, and a chair-seat supporting stretcher mounted upon the vertical extension of said yoke.

2. The combination, in a tilting and swiveling chair, of a base, a fixed guide-post rising vertically therefrom, a turn-table swiveled on the post and rotatable on the base, a yoke having an intermediary hub mounted and adapted to slide vertically upon the post, said yoke having in front of the hub a horizontally disposed extension provided with a threaded opening and in rear of the hub a vertical extension, an adjusting-screw having its lower end swiveled in the turn-table and its upper end threaded in the opening in the horizontal extension of the yoke, an operating-nut carried by the adjusting-screw, an inverted U-shaped stretcher bridging the yoke in rear of the hub thereof, a transverse pintle connecting the depending sides of the stretcher and the yoke in rear of its hub, stops depending from the stretcher in front and in rear of the 125 vertical extension of the yoke, whereby to limit the tilting movements of the stretcher, spider-arms carried by the stretcher, and a tension-device between the stretcher and said vertical extension of the yoke whereby 130

to hold the rear stop of the stretcher normally in contact with the vertical extension of the yoke.

3. The combination, in a tilting and swiveling chair, of a base, a fixed guide-post rising vertically therefrom, a turn-table swiveled on the post and rotatable on the base, a yoke having an intermediary hub mounted and adapted to slide vertically upon the post, said yoke having in front of the hub a horizontally disposed extension provided with a threaded opening and in rear of the hub a vertical extension having a transverse opening, an adjusting-screw having its lower end swiveled in the turn-table and its upper end threaded in the horizontal extension of the yoke, an operating nut carried by the adjusting-screw, an inverted U-shaped stretcher bridging the yoke in rear of the hub thereof, a transverse pintle connecting the depending sides of the stretcher and the yoke in rear of the hub, stops depending from the stretcher in front and in rear of the vertical extension of the yoke, whereby to limit the tilting movements of the stretcher, spider-arms carried by the stretcher, a bridge-piece carried by the stretcher, a threaded bolt passed through the bridge-piece and through the opening in the vertical extension of the yoke and having its head between the same and the hub, a hand-wheel on the outer end of the bolt, and a tension-spring interposed between the hand-wheel and the vertical extension of the yoke.

4. In a tilting-chair, the combination therein, of a substantially inverted U-shaped stretcher and its adjustable support, and opposite spider-arms secured to the sides of the stretcher and having their attaching-ends occurring in substantially the same horizontal plane as the upper side of the stretcher.

5. In a tilting-chair, the combination therein, of a substantially inverted U-shaped stretcher and its adjustable support, and opposite spider-arms riveted to and reinforcing the sides of the stretcher and having their attaching-ends occurring in substantially the same horizontal plane as the upper side of the stretcher.

6. In a tilting-chair, the combination therein, of a substantially inverted U-shaped stretcher and its adjustable support, and opposite spider-arms formed of angle-iron, the angles of the arms being outwardly disposed and the vertical portions of the arms being rigidly attached to and reinforcing the sides of the stretcher below the top thereof whereby the attaching-ends of the spider-arms occur in substantially the same horizontal plane as said upper side of the stretcher.

7. In a tilting-chair, the combination therein, of a yoke, a vertically adjustable support therefor, an inverted U-shaped stretcher embracing the yoke, a transverse pintle passing through the yoke and the depending sides of the stretcher, means for yieldingly holding the stretcher upon the yoke, and opposite spider-arms, angular in cross-section and having their vertical portions arranged against the depending sides of the stretcher and riveted thereto and receiving the ends of the pintle, said spider-arms having their angles outwardly disposed and their attaching-ends occurring in substantially the same horizontal plane as the upper side of the stretcher.

In testimony whereof I have signed my name to this specification in the presence of two subscribing witnesses.

HARRY W. BOLENS.
